APPARATUS FOR APPLYING BANDS TO
TUBULAR ARTICLES

William A. Weightman, Philadelphia, Pa., assignor to Edward G. Budd Manufacturing Company, Philadelphia, Pa., a corporation of Pennsylvania

Original application May 2, 1942, Serial No. 441,513. Divided and this application May 25, 1943, Serial No. 488,361

8 Claims. (Cl. 78—15)

This invention relates to apparatus for applying bands to shells, projectiles and the like, this application being a division of my application Serial No. 441,513, filed May 2, 1942.

In certain classes of ordnance work it is the practice to provide the shell or projectile with a propelling band mounted in a circumferential groove near the base thereof. The band is usually of brass or an alloy which is sufficiently soft to minimize injury of the rifled surfaces of the bore of the ordnance piece from which the projectile is to be fired. Present day high velocities impose severe stresses which tend to loosen the bands from the projectiles during passage through the guns from which they are fired and it is well known that should the bands become loosened the projectiles are quite apt to be unsteady in flight.

The aim of the apparatus of the present invention is to provide a shell, projectile and the like with a band which has the inherent characteristic of maintaining itself sufficiently tight as not to become loosened as a result of the imposition of racking stresses or of circumferential expansion arising out of the heat generated during firing.

One of the objects of the present invention is to provide an improved apparatus for banding shells, projectiles and the like whereby in the use of the apparatus the band will be efficiently and firmly applied with the insurance that it will retain a tight leak-proof fit with the shell or projectile.

Another object is to provide such apparatus wherein in its use the band will be under a state of initial tension when in place and will tend to tenaciously grip or hug the shell or projectile.

A further object is to provide an improved apparatus for banding shells and projectiles which is of simple and yet extremely efficient construction, and of such construction that the shells and projectiles can be banded with great rapidity.

With the above and other objects in view, the present invention consists in certain features of construction, combination of parts which will be apparent from the following detailed description, to be hereinafter described with reference to the accompanying drawings, and then claimed.

In the drawings which illustrate a suitable embodiment of the apparatus of the present invention,

Figure 1 is a vertical longitudinal section taken through the apparatus showing the same in the process of banding a shell.

Figure 2 is a view similar to Figure 1 showing a shell and band in position prior to the banding operation.

Figure 3 is a top plan of the segmental banding segments employed in the apparatus;

Figure 4 is a fragmentary view corresponding to the upper portion of Figure 1 but showing the banding segments in side elevation instead of in section; and

Figure 5 is a section taken approximately on line 5—5 of Figure 1.

Referring to the accompanying drawings in which like numerals refer to like parts throughout the several views, the apparatus includes a suitable frame member 10 having a horizontal table 11 provided with an opening 12 therethrough. Supported on the table 11 is an annular die or cone support 13 provided with a radially inwardly extending flange 14 which supports the guide member or cone 15 through engagement with a circumferential shoulder 16 formed on the cone 15. The cone 15 has a conical opening 17 therethrough coaxially aligned with the opening 12 of the table 11, the conical wall of the opening 17 forming the actuating and guiding means for the banding segments 18 about to be described.

The cone support 13 and cone 15 are clamped to the table 11 in axial alignment with the table opening 12 by means of an annular member 19 closely surrounding the members 13 and 15 and having upper and lower annular shoulders 20 and 21 respectively which respectively bear against the upper sides of members 13 and 15 in clamping engagement. The surrounding annular member 19 is provided with a circumferential end flange 22 which is secured to the table 11 by suitable bolts or cap screws 23. In the secured position of the member 19, shoulder 21 thereof securely clamps the annular cone support 13 against the table 11 and shoulder 20 securely axially clamps the cone 15 against the flange 14 of the support 13, thus securely locating the cone 15 coaxially with respect to the table opening 12.

Secured to the frame member 10 through the medium of suitable bolts 24 is a vertically arranged hydraulic pressure cylinder 25 having a reciprocable piston 26 therein provided with a vertically arranged piston or plunger rod 27. The plunger rod 27 is coaxially aligned with the table opening 12 and cone 15 and terminates in a supporting base 28 below the table opening 12, the base 28 having slidable bearing engagement with 55 a hardened wear plate 29 carried by the frame 10.

The support 30 for the banding segments 18 is secured to the horizontal face 31 of the base 28 by cap screws 32 and extends upwardly within the annular member 13. This support is provided with an axial recess 33 opening through its upper horizontal face 34, which face is formed with a plurality of radially arranged guiding ribs 35.

The banding segment 18, of which there are six in number, as illustrated, although any desired number may be employed, are supported on these guiding ribs 35 through complementary recesses 36 and as supported constitute a segmental frusto-conical banding member. In order to prevent axial movement of the segments 18 relative to the support 30, an annular guiding ring 37 is secured to the support 30 by bolts 38 and provided with a radially inwardly extending flange 39 to overlap flanged portions 40 of the segments 18 in guiding engagement.

It will be seen from the drawings that the conical surfaces 41 of the segments 18 are complementary to the conical wall 17 of the cone 13 and in the retracted, i. e. downward position of the plunger rod 27, shown in Figure 2, the conical segment surfaces 41 are in complementary engagement with the conical wall 17 so that when the plunger rod 27 is actuated upwardly the segments 18 will be caused by the conical wall 17 to move radially inwardly toward each other, during which movement they are guided by the radial ribs 35.

The segments 18 are contoured to provide, in their assembled relation, an axially extending passage 42. This passage is enlarged at 43 to provide coplanar shoulders 44 on the segments 18 which, as shown in Figure 2, support the open end of a shell or projectile P to be banded. The passage is again slightly enlarged at 43 to provide the segments 18 with aligned shoulders 46 which support the band B to be applied to the projectile P in circumscribing aligned relation with respect to the groove G of the projectile P within the band is to be applied.

In order to urge the segments 18 radially outwardly into contact with the conical wall 17, the lower end of the passage 42 formed by the segments 18 is shaped to provide conical surfaces 47 which engage with a conical separating element 48. The separating element 48 is axially movably mounted on the axial recess 33 of the support 30 and is urged in an upward direction by a compression spring which seats against the bottom of the recess 33 and against the element 48 through the medium of a washer 50.

The element 48 is provided with an axial opening 51 within which a rod 52 is positioned with a loose fit, the rod 52 being carried by the washer 50 and projecting upwardly therefrom and provided at its upper end with an enlarged cylindrical mandrel 53. The mandrel 53 is of such length that when the shell or projectile P is in place it will be positioned within the projectile P to underlie the circumferential groove G thereof. The mandrel 53 is also of a diameter slightly less than the diameter of the opening 54 within the projectile P to have a slight clearance therewith.

It is to be understood, of course, that the taper of the conical wall 17 is such that when the segments 18 are moved upwardly the wedging action will be such as to move the segments radially inwardly. Similarly the taper of the conical element 48 must be such that the radially inward movement of the segments 18 will cause

the element 48 to move axially downwardly against the resistance of the spring 49 whereby when the plunger rod 28 is retracted, the spring 49 will move the element 48 upwardly to move the segments 18 radially outwardly to the position shown in Figure 2.

In the operation of the apparatus, the operator thereof places the band B within the enlarged recess 45 to seat on the shoulder 46 and the projectile P over the mandrel 53 into seating relation on the shoulders 44 as shown in Figure 2, it being observed that the band B, which is of brass or other suitable alloy, to be applied within the groove G is greater in diameter than the diameter of the projectile P. I have found that an adept operator can first surround the projectile with the band and quickly drop the same into position in a single movement, the internal contour of the segments 18 being such that the band B automatically assumes its proper position within the enlarged recess 45 and upon the shoulders 46.

The operator then, through suitable control mechanism, (not shown and which may be of any well known character), actuates the hydraulic device 25 to raise the plunger rod 27 which moves the axially supported mechanism and projectile P upwardly. During this movement the conical face 17 of the guiding member 30 forces the banding segments 18 radially inwardly with great pressure to uniformly contract the band B and force the same within the groove G and the metal thereof to flow to completely and intimately surround the knurling 60 and expand to completely fill the groove G. The movement of the segments 18 is such that, in addition to upsetting or expanding the metal of the band B into the groove G, it circumferentially compresses the portion of the body of the projectile P underlying the band B into contact with the mandrel 53. The clearance between the mandrel 53 and the inner surface of the projectile is such however that the metal of the projectile body is not stressed beyond its elastic limit. The metal of the band B, however, due to the extreme amount of contraction is stressed beyond its elastic limit and the plastic flow thereof resulting from the heavy radial pressure causes the band metal to flow into intimate contact with all surfaces of the groove G. As previously explained, the conical element 48, during the inward movement of the segments 18 moves downwardly against the resistance of the spring 49, and this movement continues until it is restricted by the engagement of the projectile body with the mandrel 53. Since the mandrel is supported from the spring pressed washer 50 and the shank 52 thereof has a slight clearance with the element 48, the mandrel can shift laterally to compensate for any eccentricity of the internal surface of the projectile whereby the projectile body is uniformly contracted around the mandrel.

Upon release of the hydraulic pressure against the piston 26 and the return of the piston 26 and the banding mechanism to the retracted position shown in Figure 2, the spring 49 moves the element 48 upwardly to force the segments 18 to their separated position. The banded projectile is then removed. As soon as the banding pressure is relieved the shell body which has been contracted about the mandrel 53 restores itself to its initial stress-free condition, that is, the bottom of the groove returns to its original diameter, and in so doing exerts uniform radial pressure against the inner surface of the band B

tending to place the same under tension, thereby insuring greater resistance to rotation of the band relative the projectile body.

I am aware of the fact that bands or rings have been swaged into the grooves of projectiles, but in methods previously employed it has not been possible to get the metal of the band into as intimate a contact with all surfaces of the holding groove. According to my method, the band is placed under an initial tension by the restoration of the underlying projectile body to its stress-free condition with the result that the tension stresses thus set up in the band cause the band to so closely hug the projectile that the racking strains to which it may be subjected in use will not distort the same or loosen it from its hugging relation with the shell. Moreover, due to the fact that the band is under an initial tension on the bottom of the groove it has considerably greater resistance to expansion when subjected to heating by the burning powder gases produced during firing than is the case where such initial tension is not present.

While I have shown a single embodiment of the apparatus employed, it is to be understood that various changes may be made without departing from the spirit and substance of the invention, the scope of which is defined by the appended claims.

What is claimed is:

1. In an apparatus for banding cylindrical articles, band compressing means having a support and a plurality of segmental members arranged on said support about a common axis and being individually radially movable on said support, said segmental members having internal arcuate surfaces circumferentially aligned with each other to support an annular band and having external axially tapering surfaces, a pressure member having an axially tapered recess complementary to and in engagement with said tapering surfaces, and pressure means for effecting relative axial movement between said support and pressure member toward each other to cause radially inward movement of said segmental members whereby to radially compress a band carried thereby.

2. In an apparatus for banding cylindrical articles, band compressing means having a support and a plurality of segmental members arranged on said support about a common axis and being individually radially movable on said support, said segmental members having internal arcuate surfaces circumferentially aligned with each other to support an annular band and having external axially tapering surfaces, a pressure member having an axially tapered recess complementary to and in engagement with said tapering surfaces, spring means urging said segmental members into engagement with said tapered recess and for moving said segments radially outwardly upon relative movement of said pressure member and support axially away from each other, and pressure means for effecting relative axial movement between said support and pressure member toward each other to cause radially inward movement of said segmental members whereby to radially compress a band carried thereby.

3. In an apparatus for banding cylindrical articles, band compressing means having a support and a plurality of segmental members arranged on said support about a common axis and being individually radially movable on said support, said segmental members having internal arcuate surfaces circumferentially aligned with each

other to support an annular band and external axially tapering surfaces, a pressure member having an axially tapered recess complementary to and in engagement with said tapering surfaces, spring means urging said segmental members into engagement with said tapered recess and for moving said segments radially outwardly upon relative movement of said pressure member and support axially away from each other, and pressure means for effecting relative axial movement between said support and pressure member toward each other to cause radially inward movement of said segmental members whereby to radially compress a band carried thereby, said support and segmental members having slidably interfitting radial guide grooves and guide portions for constraining said segmental members to truly radial movement.

4. In an apparatus for banding cylindrical articles, a support, a plurality of segmental members radially movable on said support relative to the axis thereof to compress an annular band carried by said members, an annular pressure member surrounding said segmental members, said pressure member having an internal wedging surface complementary to and in engagement with corresponding surfaces of said segmental members, means for effecting relative axial movement between said support and pressure member whereby the wedging action between said surfaces moves said segmental members radially inward toward each other, and means for resiliently urging said segmental members into engagement with said wedging surface, said last mentioned means including axially tapering internal surfaces on said segmental members, a conical member engaged with said internal surfaces and being reciprocably mounted in said support and spring means urging said conical member into engagement with said internal surfaces.

5. In an apparatus for banding tubular articles, a support, a plurality of segmental members mounted on said support for radial movement relative to a common axis, and being recessed to coaxially support an annular band therebetween, said members having shoulder portions for supporting a tubular article to be banded coaxially within the band, and means for simultaneously moving said members radially inwardly to contract the band carried thereby into engagement with the tubular article.

6. In an apparatus for banding tubular articles, a support, a plurality of segmental members mounted on said support for radial movement relative to a common axis, and being recessed to coaxially support an annular band therebetween, said members having shoulder portions for supporting a tubular article to be banded coaxially within the band, a mandrel of slightly lesser diameter than the internal diameter of and arranged to extend within the tubular article supported by said members, and means for simultaneously moving said members radially inwardly to contract the band carried thereby into engagement with the tubular article, said mandrel serving to predetermine the amount of contraction of the tubular article during banding of the same.

7. In an apparatus for banding tubular articles, a support, a plurality of segmental members mounted on said support for radial movement relative to a common axis and being recessed to support coaxially an annular band therebetween, said members having shoulder

portions for supporting a tubular article to be banded coaxially within the band, a mandrel of a diameter slightly less than the internal diameter of and arranged to extend within the tubular article supported by said members, said mandrel being floatingly supported between said members for movement transversely thereof and serving to limit contraction of the tubular article during banding of the same, and means for simultaneously moving said members radially inwardly to contract the band carried thereby into engagement with the tubular article.

8. In an apparatus for banding cylindrical articles, a horizontal table having an opening therethrough, an annular member having its inner circumference defined by a conical wall,

means for supporting said member above said table substantially coaxial with said table opening, a vertically reciprocable plunger, means below said table for reciprocating said plunger, and a plurality of segmental members supported on said plunger for radial movement relative to a common axis coaxial with said conical wall, and said table opening, said segmental members having external tapering surfaces complementary to and in engagement with said conical wall and being internally recessed to support a cylindrical article to be banded and to support an annular band in surrounding relation with respect to the article.
